GUN MOUNTING

Cecil P. Caulkins, New London, Conn.

Application May 18, 1936, Serial No. 80,364
Renewed August 12, 1939

7 Claims. (Cl. 89—43)

This invention relates to an improvement in gun mountings and its object is to provide a slideable support for a gun barrel and for movable parts of a recoil mechanism therefor with the parts so interconnected that the gun barrel and the slideably supported parts of the recoil mechanism move simultaneously in opposite directions. Another object is to so proportion the weights and the paths of travel of the gun barrel and the slideable parts of the recoil mechanism that they will balance each other in all of their respective positions.

These and other objects of the invention will appear from the following specification in which I will describe the invention, the novel features of which will be pointed out in the appended claims:

Referring to the drawings,

Fig. 1 is a diagrammatic elevation of a gun barrel and of a recoil mechanism therefor supported in a mounting which is an embodiment of my invention. A part only of the gun barrel is shown and some of the other elements are shown in section.

Fig. 2 is a similar view of a modified construction which also embodies this invention.

Fig. 3 is an elevation, partly in section, of another type of gun mounting with an embodiment of my invention applied thereto.

Like characters of reference designate corresponding parts of each of the figures.

Referring first to Fig. 1, 10 is a gun barrel, and 11 its breech block. 20 is the frame of the gun mounting which in the particular example illustrated, is provided with trunnions 21 at the center of gravity of the assembly. 30 is a pressure cylinder in which is a piston 31 connected to the gun barrel by a piston-rod 32 and an arm 12. 40 is a recoil cylinder in which is a piston 41 and a piston-rod 42. 50 is a recuperator cylinder in which are floating pistons 51, 52. The pressure cylinder is connected with the recoil cylinder by an unrestricted passage 33. The recoil cylinder is connected with the recuperator cylinder by a restricted passage 43. 44 is a valve for regulating the size of this passage 43. These cylinders are stationary with the frame 20 and for diagrammatic simplification are shown as parts thereof. The cylinders 30 and 40, the passages 33 and 43 and the part of cylinder 50 between the pistons 51 and 52 are filled with oil. The parts of cylinder 50 outside of the pistons therein are filled with gas, preferably under some initial pressure.

The gun barrel 10 is slideably supported in a guide 22 formed in the frame. When at rest the

arm 12 is against the rear end 23 of the frame. The movement of the barrel to the left is limited by a collar 13 and a part 24 of the frame. 25 is another guide formed by the frame. On it is slideably supported a weight 60 which is movable between a shoulder 26 and a collar 27 on the frame. Weight 60 has an arm 61 which is connected with piston rod 42.

When the gun is fired, the barrel and the parts affixed to it move to the left. This movement imparted to piston 31 forces the oil in pressure cylinder 30 through passage 33 into recoil cylinder 40. This moves piston 41 and weight 60 to the right to balance the gun,—that is the center of gravity of the combined weights of the gun barrel 10 and of the weight 60 is maintained in a vertical plane passing through the axis of trunnions 21. This is true in all elevations of the gun barrel, it being understood, as will be known to all skilled in the art, that in actual construction the cylinders 30, 40 and 50 are disposed symmetrically about the axis of the gun barrel.

The movement of piston 41 to the right forces the oil in the front of cylinder 40 around piston rod 42, through passage 43 into recuperator cylinder 50 between pistons 51, 52. The size of passage 43 is adjusted to produce the desired check on the recoil of the gun barrel. Pistons 51, 52 are forced apart during the movement of piston 41 to the right and thus balance each other. During this movement they compress the gas in the ends of cylinder 50. The gas pressure thus built up causes the pistons 51, 52, to return to their initial positions, forcing the oil between them back into cylinder 40 moving piston 41 and weight 60 to the left and piston 31 and gun barrel 10 to the right, to their initial positions.

In Fig. 2 the pressure cylinder 30^A is shown as formed in the frame 20^A as before, but the recoil cylinder 40^A and recuperator cylinder 50^A are formed in a slideable unit 60^A supported in a guide 25^A formed in the frame.

A stationary tube 42^A passes from passage 33^A through cylinder 40^A and piston 41^A. There is but one floating piston 51^A in the recuperator cylinder.

The recoil of the gun forces the oil out of pressure cylinder 30^A, through passage 33^A and tube 42^A into the recoil cylinder 40^A to the right of piston 41^A. This causes the unit 60^A to move to the right toward its dotted line position. The weight of unit 60^A and its travel are proportioned to the weight and travel of the gun barrel so that the parts are balanced in their different relative positions.

The action of the recuperator cylinder and its piston needs no description as these parts operate in the usual way to cause the various parts of the mechanism to return to their initial positions.

In Fig. 3, the gun barrel 18 is supported in the type of mounting shown in United States Patent No. 1,934,700 issued to Gregory E. Davison, Nov. 14, 1933. This mounting comprises a vertical post 70 supported on a rotatable base 71, a cradle 72 pivoted to the post near its end, a beam 73, pivoted at 74 near the upper end of post 70. One end of the beam is connected by a link or links 75 with the cradle 72, and its other end is 15 weighted to bring the center of gravity through the center of the base 71.

In this case yokes 12^A and 12^B on the gun barrel are movable in slides 20^B in the cradle. The pressure cylinder 30^B is supported in the cradle. 20 In it is a piston 31^B connected to move with the barrel by being connected with yoke 12^B.

The weight on beam 73 is a slidable unit supported on guide 25^B and comprises a recoil cylinder 40^B, recuperator cylinder 50^B and a weight 25 60^B. The rear end of pressure cylinder 30^B is connected by a flexible tube 33^B with a tube 42^B which is stationary in relation to the beam 73. Tube 42^B extends through cylinder 40^B and through the piston 41^B therein. The other end 30 of recoil cylinder 40^B is connected with one end of recuperator cylinder 50^B by a restricted passage 43^B, the size of which may be adjusted as by means of a valve such as that indicated at 44 in Figs. 1 and 2.

35 The operation of this Fig. 3 arrangement is similar to that of the Fig. 2 arrangement. When the gun is fired and the barrel moves backward on the cradle 72, the weighted unit moves in the opposite direction on beam 73 to maintain the 40 center of gravity of the assembly over the center of the base 71. The flexibility of the tube 33^B makes it possible to elevate the gun barrel at will, and as in the other examples of embodiments of the invention, this does not disturb the 45 equilibrium of the parts.

I have illustrated and described several constructions which embody this invention, for the purpose of showing that it is not limited to any specific design. Other modifications may be 50 made within the spirit and scope of the invention and I intend no limitations other than those imposed by the following claims.

What I claim is:

1. A gun barrel, a recoil mechanism therefor, 55 a frame supporting the recoil mechanism and slidably supporting the barrel, a weight slidably supported by the frame arranged to balance the weight of the barrel, said recoil mechanism comprising a pressure cylinder, a piston therein connected to be moved by the barrel, a recoil cylinder, a fluid connection between the pressure cylinder and one end of the recoil cylinder, a piston in the recoil cylinder arranged to be acted upon by fluid displaced by the movement of the pressure 60 cylinder piston to move the weight in the opposite direction, a recuperator cylinder, a fluid connection between the other end of the recoil cylinder and the recuperator cylinder, said recuperator cylinder being arranged to return the movable parts to their initial positions.

2. A gun mounting comprising a vertical post, a cradle pivotally connected at one of its ends with the lower part of the post, a gun barrel slidably supported by the cradle, a pressure cylinder held by the cradle in parallelism with the barrel, 75

a piston therein arranged to be moved with the barrel, a beam pivoted to the upper part of the post, a connection between one end of the beam and the cradle and a weight movable on the other end of the beam, and fluid pressure means actuated by the movement of the barrel and piston in one direction for moving the weight in the opposite direction.

3. A gun mounting comprising a vertical post, a cradle pivotally connected at one of its ends 10 with the lower part of the post, a gun barrel slidably supported by the cradle, a pressure cylinder held by the cradle in parallelism with the barrel, a piston therein arranged to be moved with the barrel, a beam pivoted to the post, a connection between one end of the beam and the cradle and a weight on the other end of the beam, said weight comprising a member slidably supported by the beam, a recoil cylinder and a recuperator cylinder movable with said member, 15 a fluid connection between the pressure cylinder and the recoil cylinder including a stationary tube extending into the recoil cylinder, a piston on said tube within the recoil cylinder whereby the fluid displaced by the movement of the piston 20 in the pressure cylinder moves said member in the opposite direction, and a fluid connection between the recoil cylinder and the recuperator cylinder whereby the movement of the recoil cylinder over the piston therein builds up pressure 25 in the recuperator cylinder to return the movable parts to their initial positions.

4. A gun mounting comprising a vertical post, a cradle pivotally connected at one of its ends 30 with the lower part of the post, a gun barrel slidably supported by the cradle, a pressure cylinder held by the cradle in parallelism with the barrel, a piston therein arranged to be moved with the barrel, a beam pivoted to the upper part of the post, a connection between one end of the beam 35 and the cradle and a weight on the other end of the beam, said weight comprising a member slidably supported by the beam, a recoil cylinder and a recuperator cylinder movable with said member, a fluid connection between the pressure cylinder and the recoil cylinder, a piston within the recoil cylinder arranged to be acted upon by fluid 40 displaced by the movement of the pressure cylinder piston to move said member in the opposite direction, and a fluid connection between the recoil cylinder and the recuperator cylinder whereby the movement of the recoil cylinder over the piston therein builds up pressure in the recuperator cylinder to return the movable parts to their initial positions.

5. A gun mounting comprising a vertical post, a cradle pivotally connected at one of its ends 45 with the lower part of the post, a gun barrel slidably supported by the cradle, a pressure cylinder held by the cradle in parallelism with the barrel, a piston therein arranged to be moved with the barrel, a beam pivoted to the upper part of the post, a connection between one end of the beam and the cradle, a recoil cylinder slidably mounted on the other end of the beam, a piston in the recoil cylinder fixedly connected to the beam, a fluid connection between the pressure cylinder and the recoil cylinder at one side of the piston 50 therein whereby the movement of the barrel and piston in the pressure cylinder in one direction 55 will cause the recoil cylinder to be moved in the opposite direction.

6. A gun mounting comprising a vertical post, a cradle pivotally connected at one of its ends 60 with the lower part of the post, a gun barrel slid- 70

ably supported by the cradle, a pressure cylinder held by the cradle in parallelism with the barrel, a piston therein arranged to be moved with the barrel, a beam pivoted to the upper part of the post, a connection between one end of the beam and the cradle, a recoil cylinder and a recuperator cylinder slidably mounted on the other end of the beam, a piston in the recoil cylinder fixedly connected to the beam, a fluid connection 5 between the pressure cylinder and the recoil cylinder at one side of the piston therein whereby the movement of the barrel and piston in the pressure cylinder in one direction will cause the recoil and recuperator cylinders to be moved in 10 15 the opposite direction.

7. A gun barrel, a weight, a frame, a vertical support therefor at the center of gravity of the frame and the parts carried thereby, said frame having a guide on one side of the support for slidably supporting the barrel and another guide on the other side of the support remotely spaced from but parallel with the barrel supporting guide for slidably supporting the weight, and means actuated by the recoil movement of the barrel in its guide to slide the weight in its guide in the opposite direction to maintain the center of gravity of the parts over the support for the frame. 5 10
